UNITED STATES PATENT OFFICE.

GEORGE PAUL THOMAS, OF GLENSHAW, PENNSYLVANIA.

METAL-PUNCHING MACHINE.

1,287,137.

Specification of Letters Patent. Patented Dec. 10, 1918.

Application filed May 27, 1914. Serial No. 841,332.

To all whom it may concern:

Be it known that I, GEORGE PAUL THOMAS, residing at Glenshaw, in the county of Allegheny and State of Pennsylvania, a citizen 5 of the United States, have invented or discovered certain new and useful Improvements in Metal-Punching Machines, of which improvements the following is a specification.

10 My invention relates to improvement in machinery for punching holes in metal plates, beams, and such like articles.

In the accompanying drawings, Figure 1 is a view in side elevation of the web plate 15 of a steel sill of a freight car. It is the object of the present invention to provide a machine to punch expeditiously the rivet-holes in an article having such an arrangement of rivet-holes as is exemplified in this 20 web plate. Fig. 2 shows in plan the anvil portion of the punching machine; Fig. 3 shows the entire machine in front elevation; and Fig. 4 shows the machine in part in end elevation, and in part (through the punching-head) in vertical section.

25 Referring first to Fig. 1, it will be observed that the web plate of the car sill there shown must be punched with variously disposed rows of rivet holes: there are, first, the rows *a*—*b*, *c*—*d*, *e*—*f*, and *i*—*j*, extending all of them in parallel lines, longitudinally of the plate; there are, second, the rows *g*—*k* and *h*—*m*, extending at right angles to the rows first noted, transversely across the 30 plate; and there are, third, the rows *b*—*c* and *d*—*e*, extending obliquely with respect to the length of the plate.

35 In punching-machines now in use, the punching of the longitudinal rows and of the transverse rows of rivet-holes can readily be effected, and that in a single passage of the material through the punch. In making these car sills and other articles requiring the punching of such longitudinal and transverse rows as well as several rows of rivet holes oblique in their relative disposition, it has been the usual practice to punch the holes of the longitudinal rows by spacing-table machinery, and then to punch the 40 oblique rows by the slow method of hand

adjustment of the material beneath the punch. In the machine of my present invention all of this positioning is mechanically controlled, and the gain in speed and precision is great.

55 Referring to Figs. 2, 3, and 4, 1 is the reciprocating head of the punching-machine, equipped with the punches 10, 10^a; and 3 is the anvil portion of the machine, provided with the punching dies 20, 20^a.

60 As will be observed on comparing Figs. 3 and 4, the punches and dies are arranged in two rows, transversely of the direction of the advance of material through the punch (in a direction from left to right, Fig. 4); one 65 row consists of the two pairs of punches 10 and dies 20, and the other of a number of punches 10^a and corresponding dies 20^a. Referring again to Fig. 1, the arrangement 70 of the machine is such as to take and punch at one time two web plates such as Fig. 1 shows, arranged symmetrically, straight-edge (*i*—*j*) to the corresponding edge of the other plate. In passing through the machine, the entire line of holes *i*—*j* and the 75 transverse rows of holes *g*—*k* and *h*—*m*, are punched by the punches of the second row (the right-hand row, Fig. 4) 10^a, 20^a; while the irregular row of holes *a*—*b*—*c*—*d*—*e*—*f* is punched by the punches of the first row, 80 10, 20. If desired, the longitudinal rows, *a*—*b*, *c*—*d*, and *e*—*f*, may be punched by the punches of the second row, and only the oblique rows *b*—*c* and *d*—*e* of the rivet-holes 85 punched by the punches 10, 20 of the first row.

I come now to describe the arrangement for mechanically producing the oblique rows of holes in the plate fed longitudinally through the punch.

90 The punches and dies of one row (or certain of them, for it is manifest that details of arrangement may be modified) 10 and 20 are made movable, transversely of the path of the travel of the material through the punch, and means are provided for effecting such movement as the punching of a given piece of work progresses, to the end that a longitudinal advance of the material 95 together with the transverse shifting of 100

punch and die between successive punching strokes may result in an oblique succession of rivet-holes.

To this end punch and die 10 and 20 (and the drawings show symmetrically placed pairs of punches and dies) are, both of them, borne in blocks or holders 2 and 4 which are carried in head 1 and anvil 3 to move transversely; and means for moving them are provided. Any suitable means may be employed; I show my preferred means, consisting of a screw-shaft 21. The turning of this screw-shaft effects the transverse shifting of the holders 2 and 4; any preferred mechanical connection may be adopted to effect this end. For example, the die-block 4 may be screw-threaded and receive the shaft 21 and the punch-block 2 may be constructed for movement in unison with the die-block, by means of the pin-and-socket or an equivalent sliding connection, engagement 22 of these parts, one with the other. It will be perfectly manifest that the turning of screw 21 will shift die-block 4 and with it punch-block 2.

I have said that the punches for these oblique rows of holes are in this machine mounted in symmetrical pairs; and, referring to Fig. 3, it is apparent that the reverse threading of screw-shaft 21 at its opposite ends where it engages the symmetrically-paired blocks will afford a machine in which a turning of the shaft in one direction will cause both blocks to recede, symmetrically, while a reverse turning will cause them to approach.

The gags 23 for the punches 10 may be controlled by the hand-lever 24; but this matter is incidental, and forms no part of my present invention.

In Letters Patent No. 1,064,397, granted me June 10, 1913, I have shown and described blocks or holders for die and punch of suitable shape for ready attachment and removal to and from anvil and punching-head and for adjustment in position therein, at the same time constructed to endure the strains of service most advantageously. I preferably employ anvil and punching-head such as those of the patent referred to and shape my mechanically adjustable parts to be interchangeable with the removable and manually adjustable parts of that patent.

The turning of the screw-shaft 21, and the consequent transverse shifting of punches 10 and dies 20 is in Figs. 2-4 shown to be effected by a hand-wheel 25 carried on the shaft. An indicator for readily determining the degree of movement desired consists in a finger 26, movable in unison with the movable blocks and in its movement traversing a master strip 27. On this master strip the points of successive stopping may be indicated in advance.

The operation of the parts as thus far shown and described will readily be understood. As a pair of car sill plates such as shown in Fig. 1 advances through the machine, a proper setting of the gags of punches 10^a will insure the punching of the lines of rivet-holes *i-j*, *g-h*, and *h-m*. This is quite obvious to one acquainted with machines of this nature. The lines of holes *a-b*, *c-d*, and *e-f*, may also be punched by the punches, 10^a, if desired. However, as shown, the holes of the entire irregular row *a-b-c-d-e-f* is punched by one of the punches 10 of the first row. The row *a-b* is punched in normal manner, by the ordinary use of a spacing-table of any preferred design. When the point *b* is reached, and the last of the holes of the longitudinal row is punched, the lateral shifting of the punches 10 and the dies 20 begins. In the interval preceding each of the ensuing punching operations the punches and dies are shifted through the distance indicated by marks on the master strip 27, and, the spacing-table being effective as before, the successive punching operations are performed at the desired points. At point *c* the shifting of the punches and dies laterally ceases, until point *d* is reached, when shifting in reverse direction begins and continues to point *e*. Thereafter the punches remain unmoved.

I claim as my invention:

1. In a metal-punching machine the combination of an anvil and a reciprocatory punching-head, two pairs of complementary punching tools, one member of each pair being borne in said anvil and the other member in said punching-head, sliding connections between one of said pairs of tools, said last-mentioned pairs of tools being movable in a direction transverse to the direction of the reciprocation of the punching-head, and the other of the two said pairs of tools positioned to one side of the path of transverse movement of the movable pair of tools.

2. In a metal-punching machine, the combination of an anvil and a reciprocatory punching-head, seats in said anvil and punching-head for two rows of complementary punching tools, extending in parallelism and transverse to the path of advance of material through the machine, a pair of complementary tools mounted movably in one pair of complementary seats in anvil and punching-head, and means for moving the said pair of tools.

3. In a metal punching machine, the combination with an anvil and a reciprocatory punching head, of a die holder and punch holder mounted respectively upon said anvil and head and movable in a direction transverse to the line of reciprocation of said

head, a cylindrical punch borne by the punch holder and a coöperating cylindrical die by the die holder, a single screw rotatably mounted in a fixed bearing and engaging one of said holders for causing it to move upon the rotation of the screw, a sliding pin-and-socket connection between said holders whereby the rotation of said screw

causes both of said holders to simultaneously move equal distances. 10

In testimony whereof I have hereunto set my hand.

GEORGE PAUL THOMAS.
